UNITED STATES PATENT OFFICE.

OTTO KLAUSER, OF LONDON, ENGLAND, ASSIGNOR TO LUDWIG SCHWEIGER AND ROBERT MEIXNER, OF VIENNA, AUSTRIA-HUNGARY.

FASTENING DEVICE FOR HAIR-COMBS.

No. 876,463.

Specification of Letters Patent.

Patented Jan. 14, 1908.

Application filed November 16, 1906. Serial No. 343,709.

To all whom it may concern:

Be it known that I, OTTO KLAUSER, civil engineer, a subject of the German Emperor, and a resident of 61 Chancery Lane, London, 5 W. C., England, have invented a Fastening Device for Hair-Combs, of which the following is a specification.

This invention relates to hair combs and more particularly to such kinds of combs as 10 are used for hair ornaments, made of horn, celluloid, and the like.

Some of the hair combs as mentioned above hitherto used, have the great drawback, that the same do not keep in the hair, 15 but fall out and are consequently lost.

Now, the object of my present invention is to provide such combs with a special fastening device, by means of which the loss of combs is entirely obviated.

20 In the accompanying drawing Figure 1 shows the comb in a front view. Fig. 2 shows the comb with the cover plate omitted. Fig. 3 shows a detail.

My hair comb provided with a fastening 25 device consists essentially of the well known comb teeth 8, the upper parts 2 of which, are provided with recesses 3. In these recesses 3, I insert wires composed of the pins 7, the shaft 4, the guiding loop 6 at the fulcrum of 30 the shaft, the pressure loop 5 and the spring 9. The springs 9 rest in the recesses 3 against the inner sides of the prong 2, which are nearest to each other, while the guiding loops 6 rest in a specially formed cavity at the outer 35 edge of the recesses. The wires and recesses are covered by a plate 1 so as to allow only the pressure loops 5 to project out from the interior. (See Fig. 1).

When the comb is to be inserted into the 40 hair, the loops 5 are pressed together, whereby the points of the pins 7 part. This pressure is continued until the pins 7 disappear wholly into the interior of the upper part 2 and the plate 1. Now the comb is ready to 45 be inserted, and it is pushed so far into the

hair that the whole space between the teeth 8 is filled up with hair. As the comb arrives in its proper position as aforesaid, the pressure loops 5 are released whereupon in consequence of the now acting spring 9, the pins 50 7 approach again, embracing a portion of the hair between the teeth 8 above said pins 7, and thus the comb is perfectly secured from being lost.

In order to prevent the hair being caught 55 in any part of the fastener, and more particularly from the pressure loops 5, the latter are placed perfectly tight against the part 2. Also the comb may consist of only one piece, i. e. the cover plate 1, as used in the construction as hereinbefore described, can be omitted, and instead of this, the respective recess for the reception of the wire is worked in the whole comb piece.

The pressure buttons, or loops 5 in the 60 foregoing description, may be provided with jewels, such as diamonds, rubies and the like.

Having fully described my invention, what I claim and desire to secure by Letters Patent is:—

70 Fastening device for hair combs, comprising, in combination, the two teeth (8) provided at their upper ends with recesses 3, two fasteners consisting of the pins (7), shafts (4) guiding loops (6) at the fulcrum of the said 75 shafts, pressure loops (5) and springs (9) which are placed in the said recess (3), the guiding loops (6) being situated in suitable cavities at the outer edge of the recesses, and a plate (1) for covering the recess, substantially as described and shown and for the purpose set forth.

In testimony whereof I have hereunto set my hand in the presence of two subscribing witnesses.

OTTO KLAUSER.
